CASE

Irving Schwartz, Newton, Mass.

Application February 20, 1936, Serial No. 64,829

5 Claims. (Cl. 132—79)

This invention relates to cases, such as toilet kits and the like.

The principal objects of the invention are to provide a case which is so designed that the top or cover may be swung into an upright position and supported in such position without the use of means other than those forming an integral part of the structure of the case, and to provide a case which is of simple design and of attractive appearance, which is of strong and durable construction, and which may be quickly and conveniently set up and packed.

Further objects will be apparent from a consideration of the following description and accompanying drawing, wherein

Fig. 1 is a perspective view of a case constructed in accordance with the present invention;

Fig. 2 is a side elevation of the case;

Fig. 3 is a fragmentary section on the line 3—3 of Fig. 1; and

Fig. 4 is a fragmentary section on the line 4—4 of Fig. 1.

The embodiment chosen for illustration comprises a base or bottom, designated by the numeral 1, and a cover or top section, designated by the numeral 2, the base 1 being designed to hold sundry toilet articles, such as a hair brush, shaving outfit, etc., and the top section likewise being provided with means for holding other articles, such as a mirror, shoe horn, file, etc., as shown in Fig. 1. The base comprises an inner stiffening member 5 (Fig. 4) which may be a piece of heavy fiber board or the like relatively stiff sheet material, an inner facing 6 which extends over the inner surface of the stiffening member 5, the rear wall 10 and the cover 2, and an outer facing 7 which likewise extends over the outer surface of the stiffening member 5 and the corresponding surfaces of the wall 10 and cover 2, the facings 6 and 7 preferably being of leather or other sheet material having an attractive finish. The front and side marginal portions of the bottom 1 are provided with a continuous lip which, in effect, provides a part of the side and front walls and, as here shown, the lip consists of a stringer 8 which carries a series of fasteners 9, the stringer 8 being secured to the bottom by a row of stitches 12 which pass through the inturned edges of the outer facing 7 and underlying parts, as shown in Fig. 1.

The rear wall 10 adjoins the rear edge of the bottom 1 and comprises an inner stiffener 16 whose inner edge is spaced from the stiffener 5, as shown at Fig. 4. The inner and outer facings 6 and 7, which encase the stiffener 16, provide

a hinge or flexible joint 17 which supports the rear wall 10 for pivotal movement about the rear edge of the bottom 1. The top or cover 2 is pivotally supported by the rear wall 10 and comprises a stiffener 18 which is spaced from the stiffener 16 of the rear wall, and the inner and outer facings 6 and 7 provide a hinge or flexible joint 19 which supports the cover for pivotal movement about the rear edge of the wall 10.

The side walls 20 and 21 and the front wall 22 are carried by the cover and comprise continuous inner and outer flexible strips of leather or the like sheet material 23 and 24 (Fig. 3), the top edges of the strip being secured beneath the in-turned edges of the outer facing 7 by a row of 13 stitches 25. The ends of the side walls 20 and 21 are turned inwardly upon the rear wall 10 so as to form the inwardly extending pocket 26, as shown in Fig. 3. Gussets or the like reinforcing strips 27 overlie the inturned ends of the side walls 20 and the gussets and ends of the side walls are firmly secured to the rear wall 10 by stitches 28. The top and the front and side walls provide, in effect, a unitary structure which is pivotally mounted to swing about the upper edge of the rear wall which in turn is pivotally mounted to swing about the rear edge of the bottom 1 so that when the case is opened the rear wall 10 is folded back into substantially the same plane as the bottom member and provides a base which pivotally supports the cover, in which position the side walls 20 and 21 are effective to hold the cover in an upright position back of dead center, that is at an angular position greater than 90° relative to the plane of the bottom member, as shown by the dot and dash lines of Fig. 2.

A stringer 29 carrying a series of fasteners 30 adapted to interlock with the fasteners 9, extends from the rear edge of the side wall 20 along the top edge of the front wall to the rear edge of the side wall 21, this stringer being secured between the strips 23 and 24 by a row of stitches 31. A slider 32 (Fig. 1) is carried by the stringers, the slider having a pull 33 which is so arranged that when the cover is closed it may be drawn from one end of the rear wall to the other, thereby locking the case in closed position. When the case is open the slider is received and retained in the pocket 26 in the left-hand side (Fig. 1) of the case and when the case is closed the slider may be drawn around into and retained in the pocket 26 on the opposite side of the case.

It will be noted that when the cover of a case constructed in accordance with the present invention is open, the bottom part is readily accessible 55

from the front and both sides, and hence the different articles carried thereby may be quickly removed and replaced and the entire case may be set up and repacked quickly and conveniently.

5 It will be further noted that when the case is set up, as shown in Fig. 1, the rear wall provides a support for the cover and the side walls, and the side walls alone are effective to maintain it in open position.

10 While I have shown and described one desirable embodiment of the invention, it is to be understood that this disclosure is for the purpose of illustration, and that various changes in shape, proportion and arrangement of parts, as well as 15 the substitution of equivalent elements for those herein shown and described, may be made without departing from the spirit and scope of the invention as set forth in the appended claims.

I claim:

20 1. A case comprising a bottom member, a top member, a rear wall hinged at its lower edge to the bottom member and hinged at its upper edge to the top member, and a depending wall attached to and extending around the free margin of the 25 top member, the ends of said depending wall being fastened to the rear wall thereby to support the top member in upstanding position when the top member is open and the rear wall is folded back into substantially the same plane as the 30 bottom member.

2. A case comprising a bottom member, a top member, a rear wall hinged at its lower edge to the bottom member and hinged at its upper edge to the top member, and a depending wall attached 35 to and extending around the free margin of the top member, the ends of said depending wall being attached to the rear wall so as to permit the top member to be swung to and maintained at an upright angular position greater than 90°, relative 40 to the plane of the base member.

3. A case comprising a bottom member having a low upstanding wall extending around its side and front margins, a top member, a rear wall hinged at its lower edge to the bottom member 45 and hinged at its upper edge to the top member,

a depending wall attached to and extending around the free margin of the top member, said depending wall being in registry with said low wall of the bottom member when said top member is closed, the ends of said depending wall being attached to the rear wall so as to support the top member in an upstanding position when the top member is open and the rear wall is folded back into substantially the same plane as the bottom member, and complementary interlocking 10 fasteners carried by each of said walls for holding said top member in closed position.

4. A case comprising a bottom member, a top member, a rear wall pivotally joined at one edge to the rear edge of said top member and pivotally 15 joined at its opposite edge to the rear edge of the bottom member, said rear wall providing a pivotal support for the top member when in open position, flexible front and side walls secured at their upper edges to the top member, the rear ends of 20 the side walls being secured to the rear wall so as to hold the top member in an upstanding position when the case is open so that the rear wall is folded back into substantially the same plane as the bottom member.

5. A case comprising a bottom member, a top member, a rear wall pivotally joined at one edge to the rear edge of said top member and pivotally joined at its opposite edge to the rear edge of the bottom member, said rear wall providing a pivotal 30 support for the top member when in open position, flexible front and side walls secured at their upper edges to the top member, the rear ends of 35 the side walls being secured to the rear wall so as to provide means for supporting the top member in an upstanding position when the case is open and the rear wall is folded back into substantially the same plane as the bottom member, the bottom member having an upstanding lip registering with the free edges of the side and front 40 walls and, in effect, forming a part thereof when the case is closed, and interlocking fastening members carried by said lip and by the side and front walls.
